Primary Examiner — Susan E Krakower*Assistant Examiner* — Lisa A Grabenstetter(57) **CLAIM**

The ornamental design for head portion of a toothbrush, as shown and described.

DESCRIPTION

FIG. 1 is a front perspective view according to a first embodiment of a head portion of a toothbrush showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and

FIG. 8 is a bottom plan view thereof.

FIG. 9 is a front perspective view of a second embodiment of a head portion of a toothbrush showing our new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top plan view thereof; and,

FIG. 16 is a bottom plan view thereof.

The broken lines depicting a toothbrush head and bristles represent unclaimed portions of the design.

1 Claim, 8 Drawing Sheets# US D776,435 S
